Charles A. Fausel, Glen Ridge, N. J.

Application December 6, 1947, Serial No. 143,010

Term of patent 7 years

(Cl. D34—15)

To all whom it may concern:

Be it known that I, Charles A. Fausel, a citizen of the United States, residing in Glen Ridge, in the county of Essex and State of New Jersey, have invented a new, original, and ornamental Design for a Toy Music Box, of which the following is a specification, reference being had to the accompanying drawing, forming a part thereof.

Fig. 1 is a top plan view of a toy music box embodying my new design.

Fig. 2 is a bottom plan view thereof.

Fig. 3 is an end elevational view thereof taken in the direction indicated by arrowhead 3 in Fig. 2, and

Fig. 4 is an end elevational view thereof taken in the direction indicated by arrowhead 4 in Fig. 2.

I claim:

The ornamental design for a toy music box, as shown.

CHARLES A. FAUSEL.
